TIMING DEVICE

Robert W. Goff, Schenectady, N. Y., assignor to
 General Electric Company, a corporation of New
 York

Application December 30, 1938, Serial No. 248,499

10 Claims. (Cl. 161—1)

My invention relates to timing devices, more particularly to electrical controllers for performing a switching operation after a predetermined time interval, and has for an object the provision of rugged and reliable device of this character which affords great precision in timing over a broad range of time intervals.

The timing device embodying my invention has a wide variety of uses in the control of electrical apparatus which require precision timing control, such as, X-ray machines, knitting machines, heat-treating furnaces, and other industrial equipment. Precision timing of intervals from a few seconds to twenty minutes with accuracies within on the order of a fifth of a second variance have been obtained with a timer incorporating the features of my invention. A dial-operated time setting mechanism having a micrometer calibrating adjustment is provided to obtain such precision timing in a manner to be explained hereinafter.

A magnetic coil and armature are provided for actuating both a contact-actuating structure and a clutch interposed between a synchronous driving motor and a timing element driven thereby. A single link connects the armature with the contact-actuating structure; this link is arranged to be connected to either of two points on the contact-actuating structure so that the timing device may be operated with either a normally energized or a normally deenergized magnetic coil. In addition the link affords a simple manually adjustable means whereby the timer may be operated so that if a power failure occurs during a timing cycle, the timer will automatically reset, ready for the subsequent initiation of a new timing cycle after the power is re-turned. Or, by connecting the link to the other point, the timer may be operated so that upon the occurrence of a power failure, the timing period is interrupted until power is again applied; thereafter, the timing cycle automatically continues, and the time interval is timed out. In the latter case, the duration of the timing cycle is increased by an amount equal to the duration of the power failure.

My invention also contemplates the provision of a shock-free contact and contact-actuating structure, as more fully described hereinafter, particularly advantageous when the timing device is subjected to severe mechanical shocks and the like which would tend to affect the disposition of the contacts and interrupt the timing cycle. Further advantages and features of the

timing device embodying my invention will become apparent as the description proceeds.

For a more complete understanding of my invention, reference should be had to the accompanying drawings in which Fig. 1 is a side elevational view of the timing device embodying my invention mounted on a panel; Fig. 2 is a side elevational view partly in section of the timing element and dial-operated setting means therefor; Fig. 3 is an elevational view of a section of the right-hand end of Fig. 2 taken along the line 3—3 looking in the direction of the arrows; Fig. 4 is a simplified perspective view of the timing device embodying my invention; Fig. 5 is a circuit diagram of the timing device connected for operation with a normally energized magnetic operating coil; and Fig. 6 is a circuit diagram of the timing device connected for operation with a normally deenergized magnetic operating coil.

Referring to the drawings, the timing device embodying my invention in one form comprises a compact unitary structure which includes a frame 10 fabricated from a number of metallic stampings for supporting the various operating parts of the timer as shown in Fig. 1. The frame 10 may be mounted on a suitable panel 11. A rough outline of some of the operating parts of the timing device is now given to facilitate the understanding of a more detailed description hereinafter. As best illustrated in Fig. 4, driving means including a suitable timing motor 12, such as a constant speed synchronous capacitor motor, is provided for driving a traveling piron timing element 13, which operates a latch 14 at the end of a predetermined time interval for actuating a pair of timed contacts 15 and 16. A manually adjustable setting means including a dial 17 is provided for adjusting the starting position of the timing element 13, the length of the path of travel of the element 13 being a determinant of the timing interval. A contact-actuating structure 18 actuates an interlock contact 19 and also biases the timed contacts 15 and 16 for movement upon release by the latch 14. In addition, a magnetic operating means 20 is provided for actuating the contact-actuating structure 18 as well as for actuating a clutch 21 interposed between the timing motor 12 and the timing element 13.

The three movable contacts 19, 15 and 16 are each supported in an identical manner on resilient strips 22, 23 and 24, respectively, which are fixed at their lower ends on a support member 25 and suitably insulated since the resilient strips also act as conductors for the movable contacts. As shown in Fig. 1, the resilient strip 22

consists of a vertically extending portion interposed between two spaced-apart fixed contacts 26 and 27 and an additional portion above these contacts bent over at substantially a right angle 5 with the first position and extending to the left to form a connecting arm having a hooked end 28 which is attached to a rocker member 29 of insulating material by insertion into a slot or recess 30 therein. Although I prefer to form the 10 resilient support and connecting arm for the movable contacts as a unitary strip of conducting material, I do not intend to be limited thereto, since it will be obvious that the support and arm 15 may be made in separate parts of nonconducting material without departing from the spirit of my invention. The movable contact 19 is mounted on the resilient strip 22 having a portion extending at either side thereof in cooperating relation with the spaced-apart fixed contacts 26 and 20 27 for making contact with one or the other of the fixed contacts in accordance with the rotary movement of the rocker member 29 on its pivot 31. The fixed contacts themselves are only relatively fixed in that they are each mounted on 25 suitable resilient mountings 32 and 33 attached to the supporting terminal members 34 and 35 to which circuit conductors may be connected. Each of the resilient strips 22, 23 and 24 is identical in construction as are the movable contacts 30 19, 15 and 16 and the respectively cooperating fixed contacts 26 and 27, 36 and 37, 38 and 39, each resilient strip being attached to its own rocker member 29, 40 and 41, respectively. Insulating walls 42, such as shown in Fig. 1, may 35 be provided between the several resilient strips 22, 23 and 24 to confine and insulate the contact sections from each other.

In addition to the rocker members 29, 40 and 41, the contact-actuating structure 18 for the 40 movable contacts 19, 15 and 16 includes the shaft 31 supported by a portion 10a of the frame 10 and the spaced-apart rods 43 and 44 which are carried by a pair of links or spreaders 45 for rotation about the shaft 31 as a center. The rods 45 43 and 44 are in parallel-spaced relation to the shaft 31, one at either side thereof, and are fastened together by the links 45 so that the pairs of rods and links may be rotated as a unit on the shaft 31. The rocker members 29, 40 50 and 41, themselves loosely mounted for rotation on the shaft 31, each has a pair of arms extending transversely over the rods 43 and 44 so that rotation of the rods will cause like rotation of the rocker members.

55 To provide a resilient connection between the rockers and parallel rods, a substantially U-shaped spring 46 is mounted between the left-hand arm of each of the rocker members and the rod 43, the lower leg of the U resting on the 60 rod and the upper end of the U being fastened to the arm of the rocker by means of a screw 47. In this manner, the right-hand arms of the rockers are biased against the rod 44. Since all of the members directly connected to the fixed 65 and movable contacts are either resiliently supported or resilient strips in themselves, severe mechanical shocks will be withstood by the structure without causing the contacts to disengage and the circuits interrupted.

70 The right-hand extending arms of the rockers 40 and 41, besides resting on the rod 44 are also disposed in abutting relation with the ends of the 75 upstanding portions 48 on the latch member 14. If the latch 14 is in a latching position as shown, rotation of the rod-and-link structure 18

in a clockwise direction will bias the right-hand legs of the rockers 40 and 41 against the upstanding portions 48 of the latch 14 by means of the spring-compression forces developed as the left-hand rod 43 moves upwardly against the 5 springs 46. In the normal position of the rockers and rods as shown in Fig. 4, the movable contacts 19, 15 and 16 are biased by the resilient supporting strips 22, 23 and 24 into engagement with the back row of fixed contacts 26, 36 and 38, the 10 rockers each pulling the corresponding supporting strip to the left in this position.

When the rod-and-link structure 18 is moved in a clockwise direction from the normal position shown, movement of the first rocker 29, 15 which is free to move, and corresponding movement of the attached resilient strip 22 to the right will cause the interlocking contact 19 to move from its first position of engagement with the fixed contact 26, to a position of disengagement, and then to a second position of engagement with the front fixed contact 27, thereby again making circuit. Simultaneously, the upstanding portions 48 of the latch 14 will maintain the rocker members 40 and 41 in their normal position so that the back fixed contacts 36 and 38 will continue to be engaged by the movable contacts 15 and 16, although the rockers and movable contacts will be biased for movement into engagement with the front fixed contacts 37 and 39, 40 39 by the U-shaped springs 46 on the rockers which will be compressed as the rod 43 moves upwardly. Movement of the latch 14 in a clockwise direction on its pivot shaft 49 which is supported by portions 50 of the frame 10 will, of course, release the last two rockers for rotation in a clockwise direction by the springs 46 and cause the movable contacts 15 and 16 to disengage from the back fixed contacts 36 and 38 and engage the front fixed contacts 37 and 39, 40. The operation of the latch member 14 in conjunction with the timing element 13 will become apparent as the description proceeds.

Control of the clutch 21 is also effected by the contact-actuating rods 43 and 44, namely, the 45 front rod 44 is connected by means of a link 51 to a rotatable member 52 pivoted on a shaft 53 supported by a portion 54 of the frame 10. The rotatable member 52 has a bifurcated portion 55 which cooperates with a collar 56 on one end 50 of a sleeve 57 which is slidable on a shaft 58 fixed to and supported at its left-hand end on the frame 10. The sleeve 57 and collar 56 is normally biased for movement on the shaft 58 in a direction from left to right by means of a helical 55 spring 59 which encircles the shaft 58 and is seated on the left-hand face of the collar 56 but is restrained in position by the bifurcated portion 55 of the member 52. The right-hand end of the sleeve 57 carries a pinion 60 and at the extremity 60 a serrated clutch face 61 adapted to cooperate with a mating serrated clutch face 62 supported on a shaft 63 which is driven by the timing motor 12.

In the normal position of the contact-actuating 65 mechanism 18 as shown, the serrated clutch faces 61 and 62 forming the clutch 21 are held in a spaced-apart relationship and the clutch 21 is disengaged, the bifurcated portion 55 of the member 52 cooperating with the collar 56 on the 70 sleeve 57 to hold the sleeve in a left-hand position on its shaft 58 against the bias of the helical spring 59. Clockwise rotation of the contact-actuating structure 18 moves the rod 44 and link 51 downwardly and causes the member 52 to ro- 75

tate in a clockwise direction about its supporting shaft 53. Simultaneously, the bifurcated end 55 of the member 52 moves in a clockwise direction and permits the collar 56 and sleeve 57 to move to the right on the shaft 58 under the bias of the spring 59 for engaging the clutch 21. In this manner, the contacts 19, 15 and 16 and the clutch 21 are simultaneously actuated by the rod-and-link structure 18.

10 The contact-actuating and clutch-controlling mechanism is actuated by a single link 64 which is normally connected to the back rod 43. When the timer is operated with the magnetic means 20 normally energized. The lower end of the link 64 is connected to another rod 65 which in turn is fastened to a movable armature 66 of the magnetic operating means 20. The magnetic means 20 comprises the movable armature 66 and a cooperating energizing winding 67 therefor which when energized attracts the armature upwardly further into the winding. The rod 65 secured to the movable armature 66 and the lower end of the actuating link 64 is mounted for rotational movement about the shaft 68 by means of the pivoted links 69, the shaft 68 being carried by the supports 70 on the frame 10. A helical spring 71 encircling the shaft 68 is provided for biasing the movable rod 65 and armature 66 to the lower or normally unattracted position shown. Another spring 72 is stretched between the upper and lower rods 43 and 65 connected by the link 64 merely for the purpose of providing a conveniently detachable means for securing the link on the upper rod, the link 64 being interchangeable from the rod 43 to the rod 44, when the timer is operated with the magnetic means 20 normally deenergized.

30 As shown in Fig. 4, the link 64 is connected from the lower rod 65 to the back rod 43 of the contact-actuating mechanism 18 so that the helical spring 71 acting on the armature 66 biases the rocker members 29, 40 and 41 in a counterclockwise direction, thereby pulling the attached resilient strips 22, 23 and 24 to the left causing the movable contacts 19, 15 and 16 to engage the back fixed contacts 26, 36 and 38. In order to operate the timer and enable it to perform its switching functions, the winding 67 must be energized to move the armature 66 and the link 64 upwardly for rotating the rocker-actuating structure 18 in a clockwise direction to actuate and bias the movable contacts to the forward position. In other words, with the link 64 connected to the rod 43 as shown, the timer operates only when the magnetic means 20 is in an energized condition. By merely unfastening the spring 72 and link 64 from the rear rod 43 and attaching them to the front rod 44 of the contact-actuating structure 18, the timing device is arranged for operation with a normally deenergized magnetic coil in a manner to be explained more fully hereinafter.

50 As mentioned above, the timing motor is utilized to drive the shaft 63 and cooperating clutch 21 when engaged, and therethrough the pinion 60 which is meshed with a large gear 73 in turn meshed with the traveling pinion 13 which constitutes the timing element. The gear 73 is mounted on a suitable shaft 74 supported by the frame 10 and has adjacent thereto a conventional helical spring-resetting means (not shown) enclosed in a casing 14a which serves to return or reset the large gear 73 and also return the traveling pinion 13 to a starting position against

a stop 75 on the time adjustable mechanism, as shown, after the clutch 21 is disengaged.

Referring to Figs. 2 and 4, the time adjustable mechanism which is driven by the timing motor 12 and which is here shown set for a time interval of seven minutes comprises the timing pinion 13, the left end of which is provided with an axial tooth 76 for engaging a tooth 77 on a disk 78, the pinion 13 being mounted on a stationary threaded shaft 79 and internally threaded for axial movement on the threaded shaft 79 when the pinion 13 is rotated. Also mounted on the threaded shaft 79 and internally threaded for movement with respect thereto is the stop 75 in the form of a sleeve which is provided with a projection 80 similar to the tooth on the disk 78 for engaging a like tooth or stop projection 81 on the right end of the timing element. The disk 78 is loosely mounted on an unthreaded portion at the left end of the stationary screw shaft 79 and has a notch or cam recess 82 on its periphery into which one end of the latch member 14 is inserted. A helical spring 83 (shown by dotted lines in Fig. 4), having one end fixed to projecting stop pin 84 on the frame 10 and the other end attached to a pin 85 on the disk 78, normally biases the disk in a counterclockwise direction thereby maintaining the latch 14 in the latched position shown. The edges of another recess 84a in the disk 78 cooperate with 30 the stop pin 84 disposed therebetween to limit the extent of rotation of the disk and so limit the rotational movement of the latch member 14 on its pivot shaft 49 between the latched and unlatched positions.

As hereinbefore indicated, the time interval provided by the timer is determined by the length of the path of travel of the timing pinion 13 as it is threaded with a clockwise rotation from its starting position shown to its position 40 of engagement with the tooth 77 on the disk 78. Immediately upon engagement of the disk 78 and timing pinion 13, the disk is also revolved clockwise against the bias of its spring 83, and consequently, the end of the latch 14 is moved upwardly to rotate the latch clockwise on the shaft 49 to the unlatched position. Upon subsequent disengagement of the clutch 21, the resetting gear 73 is free to act and threads the timing pinion 13 clockwise on the threaded shaft 79 back to the starting position against the stop 75, the spring 83 again returning the disk 78 and latch 14 to the latching position.

The initial positioning or setting of the timing pinion 13 is accomplished by the micrometer 55 mechanism, best shown in Figs. 2 and 3, which comprises a large rotatable dial 86, a similar rotatable dial 87 and a lock nut 87a, the smaller dial 87 having a pair of spaced rods 88 connected thereto which slidably extend parallel to the threaded shaft 79 through suitable apertures in a disk 89 mounted on the stop sleeve 75 and secured by the set screw 90. The small dial 87 is divided into 60 divisions, each of which corresponds to one second of time, and the large dial 86 is divided into 20 divisions, a suitable Geneva gear 91 being provided for rotating the large dial 86 one division each time the small dial 87 is turned through a complete revolution.

If it is desired to set the timer for a time interval of, say, eight minutes from its present setting of seven minutes shown, it is only necessary to release the lock nut 87a and then turn the small dial 87 through one complete revolution in a counterclockwise direction which will 75

effect movement of the large dial in a clockwise direction through one division from the seven to the eight minute setting. The dials 86 and 87 may then be locked in this position by tightening the lock nut 87a. Movement of the dial 87 counterclockwise rotates the disk 89 in a similar direction and effects movement of the disk and stop sleeve 75 in a right-hand direction about the screw shaft 79. This movement tends to back the stop sleeve 75 away from the pinion 13 but since the resetting gear 78 is spring biased for rotation in a clockwise direction, as hereinbefore described, the timing pinion 13 will be rotated in a counterclockwise direction and accordingly will follow the stop sleeve 75 and its disk 89.

Special means are provided for adjusting the relative position of the stop sleeve 75 with respect to the disk 89 which rotates it in order to calibrate the dial settings and time interval originally and afford a convenient factory adjustment for the timing device. By merely loosening the set screw 90 which fastens the disk 89 to the stop sleeve 75, the stop sleeve may be screwed forward or backward on the threaded shaft 79 independently of the disk 89 and the appended dials 86 and 87. In this fashion, very fine adjustment of the position of the stop sleeve 75 is secured so that extremely accurate correspondence of the dial readings and time interval is achieved. After this fine adjustment is made, it is fixed by tightening the set screw 90.

It is believed that the operation of the timing device will be easily understood when studied in connection with the circuit diagrams of Figs. 5 and 6. The wiring connections of the circuit diagram of Fig. 5 are identical with those illustrated in Fig. 4 and the numerals applicable in these figures have been made to correspond. Fig 5 is an identical but simplified representation of the timing device, as shown in Fig. 4 in the "off" position, normally operable with an energized magnetic coil 67, the interchangeable link 64 being connected to the rear rod 43 of the contact actuating structure 18 so that the interlock contact 19 and the timed contacts 15 and 16 are in engagement with the fixed contacts 26, 36 and 38 and with the clutch 21 disengaged.

The timing device is supplied from a suitable source of alternating current L₁L₂. The conductor L₁ is connected in series circuit with a normally closed switch 92 and a conductor 93 to the fixed interlock contact 27. A normally open push button switch 94 is connected to the conductor 93 at one side and at the other side through a conductor 95 and the resilient strip 22 to the movable interlock contact 19 which is in engagement with the fixed contact 26 not connected. A conductor 96 tapped from conductor 95 leads to the energizing winding 67 of the armature 66 and by a conductor 97 to the line L₂. The motor 12 is fed from the conductor 95 by a conductor 98 and a shunted capacitance element 99 through a conductor 100 to the fixed contact 38 which is in engagement with the timed contact 18 connected by the resilient strip 24 to the line L₂.

The time controlled circuits which may, if desired, be independent load circuits are here shown as a pair of independent load leads L_{1a} and L_{1b}, respectively, connected with the main source conductor L₁ through a circuit from L₁, the switch 92, alternatively, either the push button 94 and conductor 95, or the conductor 93, contacts 27 and 18, and strip 22, to the common

conductor 96, a lead 101, the strip 22, and the contact 15 which is engaged with the contact 36 to the lead L_{1a} but which engages the contact 37 to the lead L_{1b} after operation of the timed contact. The lead L_{1a} may supply current to any desired load as soon as the timer is energized by the pressing of the start button 94 of the timer while the lead L_{1b} may do so after a predetermined time interval, as will be explained hereinafter.

With the timing device reset and ready for starting as shown in Fig. 4 and Fig. 5, the start button 94 is pressed to energize the winding 67 in a circuit including the conductor L₁, the switch 92, the switch 94, the conductors 95 and 96, the winding 67, and the conductors 97 and L₂. The armature 66 moves upwardly to engage the contacts 19 and 27 of the interlock circuit from the switch 92 through the conductor 93, the contacts 27 and 19, the strip 22 and the conductors 95 and 96 to the winding 67 thereby maintaining the armature 66 in its upper position. Movement of the armature 66, of course, causes the contact actuating structure to rotate clockwise on the shaft 31 and biases the rockers 40 and 41 against the latch projections 48 ready for tripping. Simultaneously the normally disengaged clutch 21 is engaged and the timing motor 12 energized by a circuit from the conductor 95 including the conductor 98, the motor 12, the conductor 100, the normally engaged contacts 38 and 16, the strip 24, and the line L₂. Operation of the motor 12 in a clockwise direction drives the timing pinion 13 clockwise through the engaged clutch 21 and the gears 60 and 73 causing it to thread to the left on the screw shaft 79.

After a predetermined time depending upon the initial setting of the stop 75 and pinion 13, the axial teeth 76 and 77 engage and turn the disk 78 clockwise, the latch 14 also turning clockwise on the shaft 49 to release the spring biased rockers 40 and 41 which move clockwise to disengage the timed contacts 15 and 16 from the fixed contacts 36 and 38. Consequently, the motor 12 is disconnected at the contact 38 and the load lead L_{1a} is disconnected at the contact 36 a predetermined time after the initial energization of the timing device by the momentary closure of the start button 94. The timed contacts 15 and 16, of course, immediately engage 50 their respective fixed contacts 37 and 39 upon release of the latch 14 to connect the load lead L_{1b} at the contact 37, the contact 39 not being in circuit. In other words, the load lead L_{1b} is energized a predetermined time after the initial 55 energization of the timing device. It should be understood that although I have shown and described both the timed load circuit L_{1a} and the time delayed load circuit L_{1b}, they are only intended as representative of some of the types of 60 control which can be obtained with a timing device embodying my invention and I do not wish to be limited thereto.

When the timer is connected as described above with the link 64 attached to the rod 43 of the contact-actuating structure 18, the magnet winding 67 will continue to be energized until the switch 92 is opened or until a power failure occurs on the lines L₁ and L₂. Therefore, the clutch 21 will remain in engagement preventing 70 resetting of the timer until the switch 92 is opened. Thereafter, the resetting gear 78 will return the timing pinion to its starting position, as hereinbefore described, and the contact-actuating structure 18 will return the contacts 18 to 75

the initial position shown by the force of the spring 71. Should a power failure occur at any time, the magnetic winding 67 will be deenergized, and the timing device will reset as described. Should a power failure occur during a timing cycle, deenergization of the magnet winding 67 will cause the timing cycle to cease and the timer will reset. A new timing operation then can only be initiated by pressing the 10 start button 94.

Referring now to Fig. 6, the timing device is shown connected to operate with a normally deenergized magnetic winding 67, the link 64 being connected to the rod 44 so that the spring 71 now normally biases the contact-actuating structure 18 in a clockwise direction. The timer is connected to the supply $L_1 L_2$, the conductor L_1 leading to the switch 92 and through the conductor 93 to the contact 27 as before. The push button 94 is connected from the conductor 93 through a conductor 102 to the contacts 26 and 19, the strip 22 and a conductor 103 to the motor 12 and by a conductor 104, the contacts 38 and 16, and the strip 24 to the line L_2 . A conductor 105 from the line L_2 is connected to the winding 67, and a conductor 106 back to the conductor 102. The load leads L_1^b and L_1^a are connected respectively to the contacts 36 and 37 as before, the timed contact 15 and the strip 23 being connected to the conductor 103 by a conductor 107.

The normally open start-button 94 is shown as pressed closed in the present instance in order to complete the circuit to the magnetic winding 67 for maintaining the armature 66 in the attracted position, which, because of the connection of the link 64 to the rod 44, now maintains the contact-actuating structure 18 biased in the counter-clockwise direction so that the movable contacts 15, 16 and 19 are held by the pull of the resilient strips supporting them against the back row of contacts 36, 38 and 26 with the clutch 21 disengaged. In other words, the starting position is reached by energizing the armature winding 67 since the link 64 is reversed with respect to the contact-actuating structure 18. During the time that the start button 94 is manually held closed, the motor 12 will operate, but the clutch 21 is disengaged so the timing mechanism is unaffected. However, disengagement of the clutch 21 gives the resetting gear 13 a free hand to reset the timing pinion 13 from an operated position reached in the last previous timing cycle.

After the timer is reset, as shown in Fig. 6, the push button 94 is released, the armature winding 67 deenergized, and the timing operation initiated. The spring 71 moves the contact-actuating structure 18 clockwise engaging the contacts 19 and 21, compressing the springs 46 and engaging the clutch 21. The motor 12 then operates, being connected at one side from the line L_1 through the interlock contacts 27 and 19, the strip 22, and the conductor 103 and at the other side to the conductor 104, the contacts 38 and 16, the strip 24 and the line L_2 .

The load lead L_1^a which in this instance is energized by closure of the start button 94 during the period of resetting is momentarily deenergized by release of the start-button 94, before again being energized from the line L_1 through the switch 92, the conductor 93, the contacts 27 and 19, the strip 22, the conductors 103 and 107, the strip 23, and the contacts 15 and 36. Thereafter, i. e., from the initiation of the timing cycle 75 by release of the start button 94, the load lead

L_1^a is energized until the predetermined interval is timed out and the contacts 15 and 36 disengaged by release of the latch 14. The load lead L_1^a is then energized by closure of the contacts 15 and 37 after a time delay equal to the duration of the timing cycle. Operation of the timed contact 16 at the end of the timing cycle disengages the contacts 16 and 38 breaking the circuit to the motor 12 and it stops, the clutch 21, however, remaining in engagement under the force of the spring 71 until resetting occurs by manual closure of the push button 94 as hereinbefore described.

Should a power failure occur, at anytime during the timing cycle, it merely interrupts the 15 operation of the motor 12, the clutch 21 remaining engaged under the force of the spring 71. Upon the return of power, the timing cycle is continued and the time interval timed out. In such case, the timing cycle is extended by a 20 time equal to the duration of the power failure.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

What I claim as new and desire to secure by Letters Patent of the United States, is:

1. A contact actuating mechanism having a rocker actuating structure comprising a shaft, an operating member rotatable on said shaft having lateral portions extending on opposite sides of said shaft, a rocker operated by said lateral portions mounted on said shaft having extending arms cooperating with said lateral portions for rotation in either direction thereby, a fixed contact and a cooperating movable contact, a resilient strip fixed at one end supporting said movable contact, connecting means between the free end of said strip and said rocker for actuating said movable contact when said rocker is rotated, magnetic means including an operating coil and a movable armature for operating said rocker, and means including a link connected at one end to said armature and at the other end to said operating member, said other end of said last mentioned link being arranged for connection to said operating member at one side of said shaft for actuating said movable contact in a predetermined manner when said coil is deenergized and arranged for connection to said operating member at the other side of said shaft for actuating said movable contact in said predetermined manner when said magnetic means is energized.

2. A shock-free contact-actuating mechanism comprising a rocker actuating structure including a shaft supported at each end, a pair of spaced apart operating members mounted for rotation on said shaft and a pair of rods connecting said operating members and supported thereby, said rods extending on opposite sides of said shaft in parallel spaced relation therewith, a rocker mounted on said shaft having extending arms cooperating with said rods for rotation in either direction thereby, a spring mounting between one of said arms and its adjacent rod biasing the other of said arms of said rocker toward the other of said rods, a fixed contact and a cooperating movable contact, a resilient strip fixed at one end supporting said movable contact, connecting means between the free end of said strip and said rocker for actuating said

movable contact when said rocker is rotated, magnetic actuating means for said rocker including an energizing winding, a movable armature and a spring biasing said armature to an unattracted position, and means including a single link arranged for connection between said armature and either one of said rods whereby said movable contact may be operated in a predetermined manner with said winding energized or deenergized.

3. A timing mechanism including a driving motor, means driven by said motor adapted to initiate a switching operation after a predetermined time interval comprising a gear train and a travelling pinion driven thereby, a threaded member mounting said travelling pinion along which said pinion moves axially for a predetermined distance, a cam wheel operable by said pinion at the end of its path of travel, a tripping lever actuated by said cam wheel and adjustable means including a dial for presetting the length of the path of travel of said travelling pinion, means connecting said motor to said driven means operable to be engaged and disengaged including a clutch interposed between said motor and said travelling pinion, means including a pair of interconnected rods mounted for pivotal movement about an axis substantially parallel with said rods for operating said clutch, magnetic actuating means for imparting a rocking motion to said means, a spring biasing said magnetic means to its unattracted position, a link transmitting the movement of one of said rods to said clutch, said rods also forming a portion of a contact-actuating mechanism, a plurality of pivoted rockers having extending arms cooperating with said rods, a spring mounting between the other of said rods and the adjacent arms of said rockers for biasing the other arms of said rockers toward said first rod, a pair of spaced apart fixed contacts for each of said rockers, a resilient strip interposed between each of said pairs of fixed contacts having a fixed end and a movable end attached to its adjacent rocker for movement by rotation thereof, a pair of movable contacts on each of said strips cooperating with said pairs of fixed contacts, said tripping lever cooperating with at least one of said rockers to maintain said movable contact operated thereby in a given position even after said rods have been rocked by said magnetic actuating means, and a link cooperating with said magnetic actuating means and said rods for transmitting the motion of said magnetic actuating means to said rods, said link being adapted to be connected alternatively with either of said rods for operation of the timing mechanism in a predetermined manner with said magnetic means in a normally energized and in a normally deenergized condition.

4. A timing mechanism comprising a fixed threaded member, a pinion having a threaded bore mounted on said threaded member for travel along said threaded member, a projection at each end of said pinion, means engaged by one of said projections to initiate a control function, a stop member threaded on said threaded member and engaged by said second projection in a starting position of said pinion, an adjusting member mounted for rotation substantially on the center line of said threaded member as an axis, a rod secured to said adjusting member in spaced relation with said axis and extending in parallel spaced relation with said threaded member, an annular member mounted on said stop member

for rotation on said stop member about the center line of said threaded member as an axis, a slideable connection between said annular member and said rod, and a releasable connection between said annular member and said stop member providing for rotation of said stop member on said threaded member by said adjusting member for adjustment of said starting position, said connection being releasable to release said stop member from said annular member for rotation of said stop member and adjustment of said starting position independently of said adjusting member, and spring means for returning said pinion to said starting position.

5. A contact actuating mechanism comprising a shaft, a member rotatably mounted on said shaft having portions extending at each side of said shaft, a rocker member pivotally mounted on said shaft at a point intermediate its ends and having its ends engaging said portions of said first member for rotation of said rocker member in either direction by said first member, a flexible strip bent into two portions substantially at right angles with each other, a support securing one end of said strip, a connection between the other end of said strip and said rocker member at a point spaced from said shaft so that movement of said rocker member moves the portion of said strip adjacent said rocker member longitudinally and thereby flexes the other portion of said strip about said fixed end, a stationary contact mounted adjacent said other portion, and a movable contact carried by said other portion and movable into and out of engagement with said stationary contact by said flexing of said other portion.

6. A timing mechanism comprising three switches each provided with a stationary contact and a movably mounted contact, one of said contacts being biased to an open circuit position, a second of said contacts being biased to a closed circuit position, and the third of said contacts being biased to a predetermined position, an operating coil having an armature biased to an unattracted position and resiliently connected to said movable contacts so as to operate said contacts to other positions when said coil is energized, a latch for holding said second and third contacts against movement to said other positions when said coil is energized, a driving motor, a manually operated switch for closing a circuit for said motor, said motor circuit connections including said second contact in said motor circuit, connections connecting said first switch across said manually operated switch for shunting said manually operated switch when said coil moves said first contact to its closed position, connections connecting said coil across said motor so that said coil is energized simultaneously with said motor, timing means driven by said motor for operating said latching means to release said second and third movable contacts after a predetermined time interval whereupon said contacts are moved to said other positions by said resilient connecting means, said second contact in said other position opening the circuit of said motor.

7. A timing mechanism comprising three switches each provided with a stationary contact and with a movably mounted contact, one of said contacts being biased to an open position, a second of said contacts being biased to a closed position, and the third of said contacts being biased to a predetermined position, an operating coil having an armature biased to an unattracted

position and resiliently connected to said movable contacts so as to operate said contacts to other positions when said coil is energized, a latch for holding said second and third contacts against movement to said other positions when said coil is energized, a driving motor, a normally open push button switch for closing a circuit for said motor, said motor circuit including said second contact, connections connecting said first switch across said push button for shunting said push button when said coil moves said first contact to its other position, connections connecting said coil across said motor and said second switch so that said coil is energized simultaneously with said motor, timing means driven by said motor for operating said latching means to release said second and third movable contacts after a predetermined time interval whereupon said contacts are moved to said other positions by said resilient connecting means, said second contact in said other position opening the circuit of said motor, and an auxiliary switch movable to deenergize said operating coil whereupon said armature moves to an unattracted position.

8. A timing mechanism comprising a shaft, a contact actuating structure pivotally mounted on said shaft having operating members on opposite sides of said shaft, three rocker members pivotally mounted on said shaft, each of said rocker members having one end engaging one of said operating members, resilient connecting means connecting the other end of each of said rocker members and the other operating member, a movable switch contact operatively connected to each of said rocker members, a stationary contact for each of said movable contacts, an operating coil for operating said actuating structure having an armature biased to an unattracted position, a link having one end connected to said armature and its other end arranged for connection to one or the other of said operating members for actuation of said rocker members to one or the other of two predetermined positions when said coil is deenergized, said rocker members when in one of said predetermined positions actuating one of said movable contacts to an open circuit position, a second of said movable contacts to a closed circuit position and the third of said movable contacts to a predetermined position, means for holding the rocker members for said second and third movable contacts against movement to the other of said predetermined positions when said coil is controlled to move said movable contacts to other positions, said resilient connecting means being thereby compressed, a driving motor, a manually operated switch for controlling a circuit for said coil thereby to operate said first movable contact to close a circuit for said motor in series with said second movable contact, timing means driven by said motor for operating said holding means to release said rocker members for said second and third movable contacts after a predetermined time interval whereupon said contacts are moved to said other positions by said resilient connecting means, said second contact in said other position opening the circuit of said motor.

9. A timing mechanism comprising a shaft, a site sides of said shaft, three rocker members pivotally mounted on said shaft, each of said rocker members having one end engaging one of said operating members, resilient connecting means connecting the other end of each of said rocker members and the other operating member, a movable switch contact operatively connected to each of said rocker members, a stationary contact for each of said movable contacts, an operating coil for operating said actuating structure having an armature biased to an unattracted position, a link having one end connected to said armature and its other end connected to one of said operating members for actuation of said rocker members to predetermined positions when said coil is deenergized thereby to actuate one of said movable contacts to an open circuit position, a second of said movable contacts to a closed circuit position and the third of said movable contacts to a predetermined position, means for holding the rocker members for said second and third movable contacts against movement to other positions when said coil is energized to move said movable contacts to other positions, said resilient connecting means being thereby compressed, a driving motor, a normally open manually operated switch for closing a circuit for said motor, said motor circuit including said second contact, connections connecting said coil across said motor so that said coil is energized simultaneously with said motor, connections connecting said first movable contact across said manually operated switch for shunting said switch when said coil moves said first movable contact to said other position, timing means driven by said motor for operating said holding means to release said second and third movable contacts after a predetermined time interval whereupon said contacts are moved to said other positions by said resilient connecting means, said second contact in said other position opening the circuit of said motor.

10. A timing mechanism comprising a fixed threaded member, a pinion having a threaded bore mounted on said threaded member for travel along said threaded member when said pinion is rotated, means engaged by said pinion upon travel of said pinion in one direction to initiate a control function, a stop member threaded on said threaded member and engaged by said pinion to determine a starting position for said pinion, an adjusting member mounted for rotation at least substantially on the center line of said threaded member, a connecting member secured to said adjusting member and extending in parallel relation with said threaded member, an annular member rotatably mounted on said stop member, a slidable connection between said annular member and said connecting member, a releasable connection between said annular member and said stop member providing for rotation of said stop member on said threaded member by rotation of said adjusting member for adjustment of said starting position, said connection being releasable to provide for rotation of said stop member and adjustment of said starting position independently of said adjusting member and means for returning said pinion to its starting position.
